UNITED STATES PATENT OFFICE.

WILLIAM WYNN BARTLETT, OF TORONTO, ONTARIO, CANADA.

RAILWAY-TRACK-TIE-REMOVING DEVICE.

Application filed September 12, 1924. Serial No. 737,430.

My invention relates to improvements in railway track tie removing devices, and the object of the invention is to devise simple means whereby a railway tie may be quickly removed from beneath the track rails without having first to remove the ballast from between the ties and thereby perform the operation in a minimum space of time and with a minimum amount of labour, and it 10 consists essentially of the arrangement and construction of parts hereinafter more particularly described.

Fig. 1 is a face elevation of my device showing the tie upon which it operates in 15 transverse section.

Fig. 2 is a vertical section through the centre of Figure 1 on line 2—2.

Fig. 3 is a plan section on line 3—3 Figure 1.

20 Fig. 4 is a plan section on line 4—4 Figure 1.

Fig. 5 is an enlarged detail view of the means for locking my travelling nut on the main operating threaded spindle of my device.

Fig. 6 is a sectional view on line 6—6 Figure 5.

Fig. 7 is a cross sectional view on line 7—7 Figure 4.

30 In the drawings like characters of reference indicate corresponding parts in each figure.

1 indicates one of the rails of a railway track and 2 a portion of the tie which is to 35 be removed shown extending beneath the rail and on which the rail is supported.

3 and 4 are members of a saw supporting frame. The frame member 3 comprises the bar 5 and carrying at each end a bearing 40 standard 6, inclined outward and in which are mounted a shaft 8 carrying sprocket wheels 77, and the pillars 9 and 10 formed integral with the bar 5. 11 is a threaded aperture formed at the upper end of each 45 pillar 9 and 10. The pillars 9 and 10 are rectangular in plan section. The frame member 4 comprises a horizontal bar supported upon the upper ends of the pillars 9 and 10 and provided with bosses 19 having 50 internally threaded orifices 20 in a line with the orifices 11 and through which the orifices 11 extend securing screws 21.

The bar extends outward from the pillars 9 and 10 and upon such outwardly extended ends are supported inverted U-shaped standard members 12, the side arms of which are

provided with vertical slots 13 located vertically above the shafts 8 hereinbefore referred to. 14 are shafts mounted in the slots 13, and 78 are sprocket wheels secured to the shafts 14. Each shaft 14 is mounted in a bearing member 15 from which extends a threaded stem 16 extending through an orifice 17 in the bearing member 12 and upon which is screwed a nut 18 resting upon the member 12 so that the bearing 15 is supported and hung to adjustably carry the bearing 15.

79 is an endless chain which is supported on the sprocket gears 77 and 78 so as to assume rectangular form, the lower horizontal portion extending transversely of the tie 2 between the guiding flanges 23 and 24, and the vertical portion extending up through the slotted ends of the member 4.

80 are saw teeth sections which are carried upon each of the links of the chain 79 and as they are carried transversely of the tie serve to cut the same when gradually lowered into contact therewith by means which will hereinafter be described.

I will first describe the means by which the chain 79 is manually driven.

46 is a standard frame mounted upon the frame member 4 in proximity to each end thereof and forming at its upper end a bearing support for a crank shaft 47 provided with a crank 48 which is manually operated.

49 is a sprocket wheel secured to the shaft 47 and 50 is a sprocket chain connecting the shaft 49 with a sprocket wheel 42 secured to a shaft 40 journaled in standards 39 carried by the frame member 4. 41 is a sprocket also secured to the shaft 40. 44 is a sprocket wheel secured to one of the shafts 14. 45 is a sprocket chain connecting the gears 41 and 44. It will thus be seen that the chain 79 is driven from the crank 48 which is manually turned, the drive passing from the shaft 47 through the gear 49, chain 50, sprocket 42, shaft 40, sprocket 41, chain 45 and sprocket 44 to one of the shafts 14 and the gear 78 secured thereto which carries and drives the chain 79.

I will now describe the means by which the frame formed by the members 3 and 4 is guided to move vertically.

25 is a member provided with sleeves 28 extending upward therefrom and in which the pillars 9 and 10 slidably fit. As clearly indicated in Figure 3 the sleeves 28 are divided into two portions 29 and 30 so as to leave an intervening space 31 at each side.

of the pillar and allow of the sleeve portion passing through the openings 29^x and 30^x in the member 4 so that such member as it moves downward can contact with the member 25.

The bar member 25 is secured to the rail 1 by means which I will now describe.

97 and 98 are jaw members designed to grip the side of the rail head 1^x. The jaw 10^x 97 is provided with a stem 97^x U-shaped in cross section. 99 is a horizontally extending portion of the member 98. The portion 99 is provided with a slot 100 in which the U-shaped stem 97^x has a sliding fit. 101^x is an internally threaded orifice formed in the portion 99 and into which is screwed the threaded shaft 102. 103 is a bevel gear secured to the outer end of the shaft 102. 104 is a bracket carried by the jaw member 15^x 97 and in which is mounted a shaft 105 upon which is secured a bevel pinion 106 meshing with the bevel gear 103. 107 is a square toothed gear also carried by the shaft 105 and 20^x 108 is a lever provided with a spring 25^x operated pawl 109 coacting with the teeth of the gear 107 to turn such gear in either one direction or the other.

By swinging the lever 108 and engaging the pawl 109 with the gear 107 the shaft 102 may be turned in one direction or the other to either carry the jaws into gripping engagement with the rail head 1^x or away from it to release the same.

On each side of the portion 99 of the member 98 are located loop lugs 110 and 111. 112 is a slide bar carried within the loops 110 and 111 and secured in position by means of a locking screw 112^x operated by a handle 113. 114 is a depending bracket carried by the slide bars 112 and formed integral with the slide bar 112 and the bar 25. Thus the members 97 and 98 gripping the rail head, the slide bar 112, brackets 114 and bar 25 with its sleeve 28 together form a guiding unit for the frame comprising the members 3 and 4, which unit is carried by the rail 1 so that the lower horizontal portion of the saw chain 79 extends transversely of the tie and adjacent thereto.

In order to steady the upper end of the frame 46 I provide a vertical rod 115 extending at its upper end slidably through a loop 116.

I will now describe the means by which the frame formed by the members 34 is adjusted vertically to feed the saw downward into engagement with the tie and freed from such feeding means at the end of the cutting operation so that it may be lifted and returned manually to its normal position.

32 is a vertical threaded shaft extending upward from the bar 5 and passing freely at its upper end through an aperture 33^x formed in the upper frame member 4 and

also passing freely through an orifice 26 in the bar member 25. 34 is a worm gear secured to the upper end of the threaded shaft 32.

The lower end of the threaded shaft 32 fits within a recess 34^x formed in the bar 5.

35 and 36 are arms extending from the bar 5 and through the slots 27 extending from the orifice 26 of the bar member 25 and at each side of the threaded shaft 32.

32^x is an enlargement provided at the upper end of the shaft 32 and bearing against the frame member 4 to hold the shaft from vertical movement in relation to the frame and within the orifice 33. The shaft 32 is driven by the following mechanism:

51, 52 and 53 are a plurality of annular face gears extending from the sprocket wheel 42. 54 (Fig. 7) is a standard extending upward from the frame member 4 and provided with a slotted opening 55 having a semi-circular recess at one end forming one half of a bearing aperture. 56 is a block which slides within the slotted opening 55 and is provided at one end with a semi-circular recess 58 forming with the recess 57 a bearing aperture in which one end of the shaft 59 is journaled.

61 is a standard carried by the frame member 4 and turnably carrying a bearing member 62 in which the shaft 59 is also journaled intermediately of its length.

70 is a gear wheel having a feather key connection to the shaft 59 to permit the gear being slid longitudinally of the shaft to engage with any one of the face gears 51, 52 and 53.

In order to hold the gear 70 in engagement with any one of the gears 51, 52 or 53 I provide a wedge member 66 sliding in a guideway 65 and the wedge end of which engages the outer end of the block 56.

67 is a supplemental standard carried by the frame member 4 and provided with an internally threaded orifice through which the threaded stem 68 extends from the wedge member 66.

69 is a wing nut which is screwed upon the outer end of the stem and turnably connected to the standard 67 so as to adjust the wedge member 66 inward or outward and thereby lock or unlock the block 56 to hold or release the gear in an engaging position with one of the face gears 51, 52 or 53.

It will of course be understood that the spacing between the teeth of any one of the gears 51, 52 and 53 is such as to permit the gear 70 meshing with any one of such face gears.

The gear 70 is provided with an annular grooved hub 71 with which a fork 72 engages such fork forming part of a hand operated bar 73. The bar 73 is supported intermediately of its length in a slotted lug 74 extending upward from the bearing

members 62. The outer end of the bar 73 extends through a slot 75 in the standard member 75*. The lower edge of the bar 73 is provided with a series of notches as indicated at 76 and the outer end of the bar with a knob 77¹ by which the bar may be operated.

It will be readily seen that by lifting the knobbed end of the bar 73 upward the notches 76 disengage with the lower end of the slot 75 and the bar drawn longitudinally to carry the gear 70 from one face gear 51, 52 and 53 to another to regulate the driving speed.

60 is a worm formed on the shaft 59 and meshing with the worm gear 34 secured to the shaft 32.

It will thus be seen that the shaft 32 is driven from the gear 42 driven from the crank 48 as hereinbefore described and through the face gears 51, 52 or 53, gear 70, shaft 59, worm 60 and worm gear 34.

I will now describe the mechanism by which the bar 5 forming part of the frame member 3 is carried downward by the rotation of the shaft 32 to feed the lower horizontally extending portion of the saw into engagement with the tie to cut the same as the saw is revolved as hereinbefore described.

81 and 82 are the members of a divided nut which are pivoted at 83 and 84 to the member 25, the free ends being forced apart by the spring 85.

35 In order to hold the members 81 and 82 of the nut in engagement with the thread of the shaft 32 the members 81 and 82 are provided with outwardly extending portions 86 and 87 passing through a slot 88* formed in the housing 88.

The housing 88 is carried by the member 25 and in which is slidably mounted the movable locking member 89 provided with vertical bores 90.

91 is the base plate of the housing 88 by which it is secured to the member 25. 92 are projections extending from the housing over the upper ends of the bores 90. The wall of each of the bores 90 is provided at 50 its upper end with a vertical slot 93 in which the projections 92 have movement.

94 is a notch in the lower edge of the locking member 89 provided preferably with an outwardly flaring edge 95 and into which 55 notch the arms 86 and 87 fit so as to hold the members 81 and 82 of the nut together and in engagement with the thread of the shaft 32 against the pressure of the spring 85.

96 is a handle by which the member 86 60 may be raised or lowered.

It will be understood that the parts 25 and 114 are the stationary parts of the device, all the remaining parts being movable, that is, the parts 9, 19, 4 and 5 form a rectangular frame which is movable vertically,

the parts 9 and 10 sliding in the sleeves 28 by the operation of the crank 48 and the parts driven thereby. As the shaft 32 is turned so as to screw downward through the nut members 81 and 82, the frame comprising the members 9, 10, 4 and 5 being supported thereby at 32* drops downward by gravity, the relative position of the shaft 32 to the member 4, 5, 9 and 10 remains unaltered. The saw teeth 80 and 75 sprocket chain on which the teeth are mounted being carried downward with the frame are driven against the tie by the weight of the frame exerting a constant pressure as the saw revolves and the cut is 80 made. During this operation the arms 35 and 36 pass through the slots 27.

When the cut is completed the locking member 89 is raised by the handle 96 so as to release the portions 86 and 87 of the nut. 85 The nut then springs open away from the shaft 32 permitting the frame members 3 and 4 and the parts carried thereby to be raised manually to their normal position.

As the frame is raised the arms 35 and 90 36 pass at each side of the open nut and as these members of the nut engage the converging arms 36 the nut members are forced inward to their closed position holding them in such position, the locking member being 95 then forced down by the spring 90* so that the notch 94 again straddles the portion 86 and 87.

The bar 5 which is inverted channel shaped is provided with cross spindles 37 100 on which are mounted a roller 38 against which the lower horizontal portion of the chain 79 bears to reduce the friction as the chain passes horizontally under the pressure of its supporting frame.

What I claim as my invention is:

1. A tie removing device comprising a rectangular frame, a support for guiding the frame so as to have vertical movement, a flexible saw mounted upon the frame to travel in a rectangular path in a vertical plane having the lower portion thereof extending transversely of the tie, a threaded vertical shaft carried by the frame, a nut spring held apart out of engagement with the shaft, means for forcing the members of the nut into engagement with the shaft when the frame is raised vertically to its upward position, and releasable means adapted to lock the nut into engagement with the shaft during the downward movement of the frame.

2. A tie removing device comprising a rectangular frame, a support for guiding the frame so as to have vertical movement, a flexible saw mounted upon the frame to revolve in a rectangular path in a vertical plane, having the lower portion thereof extending transversely of the tie, a threaded vertical shaft carried by the frame, a di- 125

vided nut spring held out of engagement with the shaft, releasable means adapted to lock the nut in engagement with the shaft during the downward movement of the nut, 5 a pair of opposing outwardly flaring inclined arms carried by the lower portion of the frame at each side of the nut and adapted to engage the open nut when the frame is raised vertically to force the nut 10 into engagement with the shaft.

3. A tie removing device comprising a rectangular frame, guiding means supporting the frame so as to move vertically, means for clamping the guiding means to 15 a rail, a flexible endless saw mounted to revolve in a vertical plane upon the frame so that the lower portion thereof extends transversely of the tie, a threaded vertical spindle carried by the frame, a divided nut 20 carried by the guiding means in engagement with the thread of the shaft, projections extending outward from each member of the nut and a notched spring-held locking member carried by the guiding means,

the notch of which is adapted to receive the 25 projections of the nut to hold the members thereof together.

4. A tie removing device comprising a rectangular frame, guiding means for supporting the frame to move vertically, clamping means for securing the guiding means to the rail, a vertically threaded shaft carried by the frame, a flexible saw mounted to revolve upon the frame in a vertical plane so that the lower portion thereof extends 35 transversely of the tie, a nut carried by the guiding means in engagement with the thread of the shaft, a manually operated sprocket drive for the saw, a worm gear secured to the threaded shaft, a worm shaft 40 and worm engaging the worm gear, a driving gear mounted upon the worm shaft and keyed thereto so as to have free longitudinal movement, and a plurality of annular gear rings formed upon one of the sprockets 45 of the aforesaid drive with which such gear is slidably moved into engagement.

WILLIAM WYNN BARTLETT.
